UNITED STATES PATENT OFFICE

162,998

GOGGLE FRAME

Helmut G. Tietje, Cresskill, N. J., assignor to Columbia Proteksite Co. Inc., Carlstadt, N. J., a corporation of New Jersey

Application December 21, 1950, Serial No. 13,524

Term of patent 3½ years

(Cl. D57—1)

To all whom it may concern:

Be it known that I, Helmut G. Tietje, a citizen of the United States and resident of Cresskill, in the county of Bergen, State of New Jersey, have invented a new, original, and ornamental Design for a Goggle Frame, of which the following is a specification, reference being had to the accompanying drawing, forming a part thereof and of which:

Fig. 1 is a top plan view of a goggle frame showing my new design, and

Figs. 2 and 3 are front and side elevational views, respectively, thereof.

I claim:

The ornamental design for a goggle frame, as shown.

HELMUT G. TIETJE.
